UNITED STATES PATENT OFFICE.

SYDNEY A. METCALFE, OF CHICAGO, ILLINOIS.

TOY BUILDING CONSTRUCTION.

1,426,087.

Specification of Letters Patent. Patented Aug. 15, 1922.

Application filed June 30, 1921. Serial No. 481,458.

To all whom it may concern:

Be it known that I, SYDNEY A. METCALFE, a subject of the King of Great Britain, residing at Chicago, in the county of Cook 5 and State of Illinois, have invented certain new and useful Improvements in Toy Building Constructions, of which the following is a specification.

My invention relates to toy building constructions and has for one of its objects the provision of simple and efficient blocks and sheet material arranged so that children may easily form buildings of various sizes and shapes using a number of the blocks and 15 sheets corresponding to the size of building it is desired to build.

A further object is the provision of blocks having slots in their ends and sheets with notches in their edges so as to hold the 20 blocks and sheets in various positions necessary in making toy buildings, and other toys.

Other objects will appear hereinafter.

An embodiment of my invention is illustrated in the accompanying drawings, forming a part of this specification, and in which—

Fig. 1 is a view of a building constructed with my improved blocks and sheets;

Fig. 2 is a construction of a building with my improved blocks and sheets with one side of each room open so that access may be obtained to each of the rooms of the building;

Fig. 3 is a block shown in perspective embodying my invention;

Fig. 4 is a view similar to Fig. 3, but showing fewer slots in the block;

Fig. 5 is a piece of sheet material used for trimming around the top of the building;

Fig. 6 is a view of a sheet of material used for making the walls, floors and roof of the building;

Fig. 7 is a piece of sheet material used 45 for making the foundation of the building; and

Fig. 8 is a view similar to Fig. 6, but showing notches formed in its edges intermediate its corners.

Referring more particularly to the drawings, I have indicated in Fig. 3 a block 9, such as I prefer to use. This block is approximately square in transverse section and substantially twice as long as wide. In 55 each end I preferably form two slots 10 and 11 at right angles to each other, which

may be saw-kerfs, and preferably of depths equal to one-fourth the length of the block. It will be apparent that the depth of these cuts may be altered in accordance with the 60 notches of the sheet material to be described later.

In Fig. 4 I have shown the block 9 as having slots 10 only, and in this construction the extra labor required to cut the slots 11 will be saved. In some parts of the building the slots 11 will not be necessary.

In Fig. 6 I have indicated a substantially square piece of sheet material having indications thereon representing window and 70 wall constructions. It will be apparent that the indications on the wall may represent any part of the building it is desired to build. At the corners of the sheet 12 I have formed notches 13, and each of the 75 notches is substantially as wide and high as the depth of slot 10.

In Fig. 5 I have indicated a narrow strip 14 of sheet material having two notches 13 in its lower edge and these notches are of substantially the same shape and size as the notches 13 in sheet 12. When the parts 12 and 14 are arranged in a building a block 9 will fit into adjacent notches 13, as clearly indicated in Figs. 1 and 2, and hold the adjacent edges of sheets 12 and 14 tightly together. It is intended that the slots 10 and 11 should have widths so as to frictionally engage the sheets 12 and 14 to hold the building together and be easily taken apart 90 when so desired.

In Fig. 7 I have indicated a narrow sheet of material 15 wider than sheet 14, but it will be apparent that the widths of sheets 14 and 15 may be varied as desired. The 95 sheet 15 also has the notches 13 in certain of its corners, such as the two upper corners indicated, and these notches 13 are also of similar size to the notches 13 in sheet 12 so that blocks 9 can hold sheet 15 to the 100 under edge of sheet 12 and so that the adjacent edges thereof will be substantially together. Where a building construction is to be of one story each side can have a foundation sheet 15, one wall sheet 12, and one trimming sheet 14 to make its height. Where the building is to be more than one story high then additional sheets 12 will be used and held together by blocks 9, as indicated in Fig. 1.

It will be apparent that configurations may be printed or formed on both sides of

sheets 12, 14 and 15 when so desired so that they can be used for different kind of sides of a building.

In fitting a block to the sheets the portion of the block between the slots engages the edge portions of the sheets so that the notches must be sufficiently large to permit the block to be set in and allow the edges of the sheets to come together.

10 In Fig. 2 I have indicated a doll-house in which one side of the building is left open so that a child can place its toys in any room desired. In this form of building I have indicated the sheets 16 shown in Fig. 15 8, the only difference being that the notches instead of being at the corners of the sheets are in the edges intermediate the corners, as indicated at 17. In this form of sheet the notches 17 are of substantially the same 20 depth as notches 13, but twice as long so that the slots of a block can engage the edges of a sheet 16 at the ends of the notch 17 and the portion of the block between the slots engage said notch 17, as clearly indicated in said Fig. 2. With this construction the horizontal walls are held more firmly than with the construction using sheet 12, as indicated in Fig. 1. However the same blocks are applicable to both constructions, 30 the only difference being in the position of the notches in the sheets. I prefer to make the sheets referred to of cardboard, but any desirable substance may be used.

From the above it will be apparent that 35 buildings of various sizes and shapes may be formed by using three sizes of sheets, such as indicated, and one form of block, it being understood that the form of block in Fig. 4 may be used some places, as clearly 40 indicated in Fig. 1, on account of its more economical construction.

I claim:

1. A toy building construction comprising blocks substantially square in transverse 45 cross-section and of substantially twice the length of their widths with slots in their ends, and rectangular sheet material pieces having notches in their corners with the edges of said sheets adjacent said notches 50 engaging said slots and held by said blocks in building formation.

2. A toy building construction comprising blocks substantially square in transverse section and substantially twice as long as wide, each block having a slot in its end, 55 and rectangular sheet material pieces having notches in their corners, the edges of said sheets being adapted to engage said slots and the portions of said blocks between said slots being adapted to engage said 60 notches.

3. A toy building construction comprising a building having a plurality of substantially square sheets forming its walls, there being notches in the corners of said sheets, 65 and blocks having slots therein engaging edge portions of said sheets, the portions of said blocks between said slots being in engagement with the notches of said sheets.

4. A toy building construction comprising 70 a plurality of relatively narrow sheets with notches in their upper corners, a plurality of square sheets having notches in all their corners, substantially narrow sheets having notches in their lower corners, blocks 75 having slots at right angles to each other in each end thereof, said slots engaging edge portions of two adjacent sheets, and two adjacent notches engaging each block between the slots of the latter.

5. A toy building construction comprising 80 upright walls formed of a plurality of rectangular sheets with notches in their edges, and blocks having slots in their ends with each slot substantially one-fourth the depth 85 of the length of its block and said blocks engaging said sheets adjacent the notches thereof to lock the sheets in the form of a building.

6. A toy building construction comprising 90 a wall having two sheets of material in edge to edge relation with registering notches in adjacent edges, and a block having a slot in each end, the distance between the remote 95 sides of said notches being substantially the same as the distance laterally through said block.

In testimony whereof I have signed my name to this specification on this 27th day of June, A. D. 1921.

SYDNEY A. METCALFE.
